(57) **CLAIM**

The ornamental design for a inflatable paddling device, as shown and described.

DESCRIPTION

FIG. 1 is a front view of an inflatable paddling device showing my new design;

FIG. 2 is a back view thereof;

FIG. 3 is an enlarged partial view of the top portion;

FIG. 4 is a perspective side view thereof; and,

FIG. 5 is a side elevational view thereof, showing the invention in an inflated position.
